UNITED STATES PATENT OFFICE.

ROGER CRILLY, OF ELIZABETH, NEW JERSEY.

APPARATUS FOR DEHYDRATING TAR.

Application filed May 20, 1927. Serial No. 192,937.

This invention relates to a method and apparatus for dehydrating tar.

The object of the invention is to utilize a steam jet which atomizes the tar emulsion, carrying off the water and allowing the tar to fall by gravity to the point of accumulation.

A further object is to provide an apparatus of the character stated in which a tank is employed for receiving a tar emulsion and from which the emulsion is drawn and atomized by a steam jet, the steam carrying off the moisture and the tar permitted to return to the bottom of the tank.

15 A further object is to supply an apparatus of this character from which the dehydrated tar may be drawn after the operation is completed.

With these and other objects in view the 20 invention consists in certain novel features of construction and combinations and arrangements of parts, which will be more fully hereinafter described and pointed out in the claims.

25 In the accompanying drawings—

Figure 1 is a view, mainly in longitudinal section but partly in elevation, illustrating my improved apparatus;

Figure 2 is a view in longitudinal section 30 through the steam jet.

1 represents a tank in which a tar emulsion 2 is deposited. 4 represents a pipe coupling having four nipples. A vertical pipe 5 communicates with the lower nipple 35 of the coupling 4 and has a T-head 6 at its lower end adjacent the bottom of the tank 1. 7 represents an emulsion lifting steam jet having a supply steam pipe 8 communicating therewith, with a cock 9 controlling the passage of steam. This jet 7 is connected by a pipe 10 with one of the nipples of the pipe coupling 8, and a discharge pipe 11 is connected to the opposite nipple of said coupling 4.

45 The upper nipple of the coupling 4 is normally closed by a removable plug 12, but when the plug is removed a tar withdrawal pipe 13 may be attached to the coupling, as indicated by dotted lines in Figure 1. 14

50 represents a pipe which is connected to the

bottom of the jet 7 and extends down into the tank 1 the desired distance.

After the tar emulsion is deposited in the tank 1 a separation of the tar and water will take place by gravity.

55 The operation of the apparatus and method is as follows:

The cock 9 is opened and the passage of steam through the jet 7 will draw the emulsion up through pipe 14 and discharge it 60 through pipe 10. The tar being heavier and more sluggish than the water or steam will pass down the pipe 5 and the water will flow through the pipe 11 to any desired outlet. This operation is repeated until the dehydrating process is ended, when the plug 12 is removed. The pipe 13 connected to the coupling 4 will draw off the tar to a tank or other depository.

65 It is this broad idea of the utilizing of a steam jet for dehydrating tar emulsion which constitutes the broad idea of my invention, and while I have illustrated what I believe to be a preferred embodiment of my invention it is obvious that various changes and 70 alterations might be made in the general form of the parts described without departing from my invention and hence I do not limit myself to the precise details set forth but consider myself at liberty to make such 75 changes and alterations as fairly fall within the spirit and scope of the appended claims.

80 I claim:

1. An apparatus of the character described, including a tank adapted to receive a tar emulsion, a pipe coupling having four nipples and located above the tank, a plug normally closing the upper of said nipples, a vertical pipe communicating with the lower of said nipples and having its lower end adjacent 85 the bottom of the tank, aligned horizontal pipes connected to the other of said nipples, a steam jet connected to one of said last mentioned pipes, and a vertical pipe connected 90 to the bottom of the steam jet and projecting 95 into the tank.

2. An apparatus of the character described, including a tank adapted to receive a tar emulsion, a steam pipe coupling having four nipples and located above the tank, a plug 100

normally closing the upper of said nipples, a vertical pipe communicating with the lower of said nipples and having its lower end adjacent the bottom of the tank, aligned horizontal pipes connected to the other of said nipples, a steam jet connected to one of said last mentioned pipes, a vertical pipe con-

nected to the bottom of the steam jet and projecting into the tank, said plug adapted to be removed, and an outlet pipe connected 10 to the coupling for drawing off the tar from the bottom of the tank.

ROGER CRILLY.
